UNITED STATES PATENT OFFICE.

WILLIAM H. WRIGHT, OF BUFFALO, NEW YORK, ASSIGNOR, BY DIRECT AND MESNE ASSIGNMENTS, TO WRIGHT-HIBBARD INDUSTRIAL ELECTRIC TRUCK CO. INC., OF BUFFALO, NEW YORK, A CORPORATION OF NEW YORK.

ELECTRICAL INDUSTRIAL TRUCK.

1,404,419.

Specification of Letters Patent. Patented Jan. 24, 1922.

Application filed July 13, 1917. Serial No. 180,466.

To all whom it may concern:

Be it known that I, WILLIAM H. WRIGHT, a citizen of the United States, residing at Buffalo, in the county of Erie and State of New York, have invented certain new and useful Improvements in Electric Industrial Trucks; and I do hereby declare the following to be a full, clear, and exact description of my invention, such as will enable others skilled in the art to which it appertains to make and use the same, reference being had to the accompanying drawings, and to figures and references marked thereon, which form part of this specification.

Like figures of reference refer to like parts.

The invention relates to new and useful improvements in industrial trucks, and more particularly to an industrial truck which is driven by means of an electric motor and wherein the load is carried by a platform or support which is likewise raised and lowered by power.

One of the objects of the invention is to provide an industrial truck of the above character wherein a single motor may be used for propelling the truck and also for raising and lowering the lift platform carrying the load.

A further object of the invention is to provide an industrial truck of the above character wherein the motor is controlled by independent controllers or controlling devices when operated for driving the truck and when operated for raising and lowering the lift platform, whereby the controlling device for the motor, when used in raising and lowering the platform, may be automatically thrown out so as to stop the motor and the movement of said platform.

A still further object of the invention is to provide a brake mechanism for the moving parts which raise and lower the platform, which brake mechanism is automatically actuated with the throwing out of the controller for the motor.

Another object of the invention is to provide an industrial truck of the above character wherein an automatic switch and brake mechanism are associated with the motor and the mechanism driven thereby for propelling the truck, said switch and brake being controlled by a foot lever ad-

jacent a step-board for carrying the operator.

These and other objects will in part be obvious and will in part be hereinafter more fully disclosed.

In the drawings, which show by way of illustration one embodiment of the invention:

Figure 1 is a side elevation of a truck embodying the invention;

Fig. 2 is an end elevation of the truck;

Fig. 3 is a top plan view of the truck;

Fig. 4 is a perspective view of the truck supporting wheels;

Fig. 5 is an end elevation of the parts at the forward end of the truck;

Fig. 6 is a perspective view of the gear box containing the train of mechanism for raising and lowering the platform, and also showing the controller for the motor and the means for automatically throwing out the controller;

Fig. 7 is a perspective view of a portion of the gear box and showing the brake mechanism which is operated upon the throwing out of the controller;

Fig. 8 is a view, partly in side elevation and partly in section, showing more or less diagrammatically the elevating means for the platform;

Fig. 9 is a view in side elevation, showing more or less diagrammatically the supporting wheels and the steering mechanism for controlling the same;

Fig. 10 is a view in side elevation showing the automatic switch and the brake controlled by the step-board;

Fig. 11 is a sectional view on the line $\alpha-\alpha$ of Fig. 12;

Fig. 12 is a view, partly in plan and partly in section, of the same, also showing the motor; and

Fig. 13 is a sectional view showing one of the springs for raising the step-board when released from the operator's weight.

The invention consists broadly in an industrial truck having a supporting frame which is mounted upon a pair of driving wheels and a pair of supporting wheels. The supporting wheels are disposed adjacent the front end of the truck, while the driving wheels are adjacent the rear end of the truck. Mounted on the frame is a sup-

porting bracket carrying a motor, which is utilized both for the propelling of the truck and also for operating a lifting platform or carrying means on which the load is transported from one point to another. Also mounted on the frame is a train of mechanism which may be connected to the motor and which is connected to the driving wheels so that the motor may be used for the purpose of propelling the truck. A second train of mechanism is mounted on the frame and may be connected to the motor and is connected to a lifting or elevating mechanism for raising and lowering the platform.

15 The connecting devices between the motor and the two trains of mechanism or gearing, one of which operates the lift platform and the other of which propels the truck, are so constructed as to connect the motor with either the one train of mechanism or the other. Mounted on the frame, and independently of the mounting of the motor and the trains of mechanism above referred to, are bracket plates which support a box or housing for a storage battery, which storage battery is located above the motor and the trains of mechanism just described. A suitable controller is arranged intermediate the storage battery and the motor so that 30 the motor may be actuated when connected with the train of mechanism for propelling the truck for giving three forward speeds and three reverse speeds. An entirely independent controller is disposed between the 35 battery and the motor for causing the motor to be actuated for operating the train of mechanism which raises and lowers the platform. This last-named controller is automatically thrown out when the platform reaches either extreme of its movement. At 40 the same time that the controller is thrown out, a brake is applied to the train of mechanism which raises and lowers the platform for stopping the same. An automatic switch 45 is also included in the circuit which leads from the storage battery to the controller for the motor for propelling the truck, and associated with this automatic switch is a brake.

50 The automatic switch and brake are in turn controlled by a foot lever and step-board on which the operator rides, and this step-board is spring-operated so that when the operator's weight is removed therefrom 55 the automatic switch is cut out and the brake applied, which insures that the operator shall be in position on the step-board in order to operate the motor for propelling the truck. Suitable steering means is arranged so as to be accessible to the operator 60 while standing on the step-board.

65 The invention will be made more clear by reference to the drawings, wherein the frame of the truck is shown as including two I-beams 1 and 2, forming stringers

which are rigidly connected by plates 3 and 4 secured to the underside of the I-beams. Mounted on these I-beams and extending beyond the ends thereof are inverted T-bars 5 and 6. These T-bars are used to connect the main frame to the driving axle. Mounted on the T-bars are bracket plates 7 and 7^a, the upper ends of which are connected by a bar 8 which may be used as a hand bar by the operator. Rigidly secured to one of the plates 7 is an angle bar 9 which is formed with a horizontal section 10 and a vertical section 11, said vertical section being connected to the T-bar 5. A similar angle bar is connected with the plate 7^a and the T-bar 6. The sections 11 of these angle bars are connected by a cross plate 12. These bracket plates and angle bars form a framework on which the box or housing 84 for the batteries is mounted. The batteries are located within this box or housing.

As a means for carrying the front supporting wheels I have provided cross bars 13 and 14 which are rigidly secured to the I-beams 1 and 2, and in these cross bars is journaled a longitudinally extending bar 15 provided with a circular portion or fifth wheel 16, which engages a similar portion 17 connected to the axle frame 18. Journaled upon the axle frame 18 are the supporting wheels 19 and 20. The axle frame has a projecting portion 21, to the outer end 22 of which is pivoted a steering bar 23. This steering bar is utilized for turning the axle about its pivotal support on the bar 15, and it will be obvious that the bar 15 may rock in its journals so as to provide a very efficient supporting means for the truck frame even though the floor or ground on which the truck rests is more or less uneven.

The propelling wheels, as above noted, are located near the rear end of the frame and are indicated at 28 and 35 in the drawings. Fixed to the T-bar 6 is a yoke bracket 24 to which is vertically pivoted a forked bearing piece 25. This bearing piece 25 has a tubular extension 26 which carries the hub 27 of the wheel 28. The hub is journaled on the extension by means of ball bearings 29. Rigid on the end of the hub is a disk 30 which is connected with a stub shaft 31. The inner end of the stub shaft 31 terminates in a universal joint 32, the pivot points of which are in line with the pivot points 33 and 34 of the yoke 24. The wheel 35 is mounted in a similar manner. Said wheel has a hub 36 rigidly fixed to a disk 37 which in turn is rigidly fixed to a stub shaft 38. Said hub is journaled on a forked piece 39 pivoted to a yoke bracket 40 which in turn is supported by the T-bar 6. The shaft 38 is connected by a universal joint 42 to one section of a driving cross shaft 41. The shaft 31 is connected with the other section of this shaft 41 by the

universal joint 42. The forked piece 39 has an integral arm 43, and the forked piece 24 has a similar arm 44. A rod 45 is pivotally connected to these arms 43 and 44 and serves 5 as a means for turning the wheels 28 and 35 on their pivotal supports to aid in the steering of the truck. The arm 44 has an extension 46 which is pivotally connected to the steering rod 23, which as noted above is in 10 turn connected to the front wheels for turning the same when steering the truck. It will thus be seen that by movement of the steering rod 23 the rear wheels will be turned on independent pivotal supports, while the 15 front pair of wheels will turn about a common pivotal support.

Referring more particularly to Fig. 9, it will be noted that the steering rod 23 is operated by means of a hand lever 47. This 20 hand lever is pivoted to the side bracket plate 7^a at 48. Pivotally connected to the hand lever 47 is a rod 49 which in turn is pivoted to a bell crank 50 at the point 51. The bell crank 50 is pivoted at 52 to the 25 frame of the truck. This bell crank has a downwardly extending arm 53 which is pivoted to a rod 54, one end of which is connected by a rod 55 to a sleeve 56 rigidly fixed to the steering rod 23. The lever 47 is 30 moved in a vertical direction, for example, to the position shown in dotted lines at 47^a, when turning the wheels for steering the truck, and this brings about a movement of the bell crank 50 and the parts connected 35 thereto for shifting the steering rod 23 to simultaneously turn the driving wheels and the supporting wheels.

The driving shaft 41, as above noted, is formed in sections which are connected respectively with the wheels 28 and 35 for propelling the same. The sections of the shaft 41 are connected with a differential set of gears of the usual type. Said gears, as herein illustrated, consist of a beveled gear 45 which is connected to one part of the shaft 41 and a similar beveled gear which is connected with the other part of the shaft 41. These gears 57 and 57 mesh with four beveled pinions 58, 59, 60 and 61 which are 50 carried by and moved bodily with a spur gear 62.

Rigidly mounted upon the rear axle of the truck and positioned above the shaft 41 is an electric motor 63 which is connected to and 55 operates the shaft 64. This shaft is journaled in suitable bearings carried by the axle of the truck. Said motor is mounted on a bracket 63^a which in turn is rigidly supported by the frame of the truck.

60 Loosely journaled upon the shaft 64 of the motor is a sleeve 65 which is formed at one end with an internal clutch gear, the teeth of which are pointed at the outer face of the gear, and at the other end of said shaft is 65 a pinion 66. The pinion 66 is adapted to

mesh with a gear 69 fixed to a shaft 70 which is journaled in suitable brackets on the axle of the truck. Fixed to the shaft 70 is a pinion 71 which meshes with the gear 62 of the differential. The shaft 64 is provided with 70 a portion which is square in cross section, as indicated at 72. Mounted on this square portion of the shaft 64 is a sleeve 73 which is fitted to the cross section of the shaft so that said sleeve turns with the shaft. This sleeve 75 is formed with a pinion 74 at one end thereof which is of the proper size and shape to fully pass into the internal gear 67 and engage the teeth 68 thereof. Said sleeve 73 is provided with a section 75 at its opposite 80 end which has a recess 76 adapted to receive the ends 77 and 78 of a yoke piece 79. This yoke piece 79 has sliding engagement with a supporting pin 80 fixed in a bracket carried by the axle of the truck. Extending upwardly from the yoke piece 79 is a lug 79^a. Loosely passing through an opening in this lug is a rod 81. A nut 79^c is threaded onto the rod before it is inserted into the opening, and then a nut 79^b is threaded onto the 90 other end of the rod. A coiled spring 79^e is disposed between the nut 79^c and the lug, and a separate coiled spring 79^d is disposed between the nut 79^b and said lug. These 95 springs tend to hold the lug 79^a in an intermediate position, and at the same time will permit a yielding pressure to be applied to the sleeve 73 for shifting the pinion 74 into mesh with the internal gear for connecting the motor with the driving wheels for propelling the truck.

The rod 81 is pivoted at the lower end of a lever 82, as shown in Fig. 2 of the drawings. This lever 82 is pivoted at 83 to the battery box or housing 84. Fixed to said 105 box 84 is a stop piece 82^a having a central lug 82^b against which the lever 82 rests on either side thereof but over which lug the lever can pass so that the lever may be placed on either side of said lug 82^b and will 110 rest against the same.

As a means for raising the lift platform, the pinion 74 may be caused to mesh with a gear 85 which is connected through a train of mechanism to the lifting devices for the 115 platform. The teeth of the gear 85 on the side thereof adjacent the internal gear 67 are pointed so as to facilitate the meshing of the pinion 74 therewith. Both ends of the teeth on the pinion 74 are pointed to 120 further facilitate the intermeshing of the teeth of this pinion with either the internal gear 67 or the gear 85. The gear 85 is rigidly fixed to a shaft 86 which is journaled in an extension 87 of the gear box 88. A 125 beam 90 connects the extension 87 on the gear box with the bearing 89 of the motor and insures the proper relative positions of the axes of the shafts 64 and 86. Journaled in the lower part of the gear box 88 is a 130

shaft 91 which is connected to the shaft 86 by means of a train of reduction gears. This train of gears consists of a pinion 92 keyed to the shaft 86 and meshing with the gear 93 journaled on a shaft 94. Rigidly fixed to and concentric with the gear 93 is a pinion 95 which meshes with a gear 96 journaled upon the shaft 91. Rigidly connected with the gear 96 and journaled upon the shaft 91 is a pinion 97 which in turn meshes with the gear 98. Rigidly connected with the gear 98 is a pinion 99 which meshes with a gear 100 keyed to the shaft 91. The shaft 91 is mounted in journals 101 on the outside 15 of the box 88, and a crank piece 102 is carried by the end of the shaft 91. This crank piece 102 is pivoted to a rod 103 which is moved back and forth for elevating the platform. From the above description, it 20 will be apparent that this crank piece 102 is operated from the motor shaft by means of the pinion 74 meshing with the gear 85 and through this reduction train of gearing.

The means for raising and lowering the 25 platform consists of inclined blocks 104—104 mounted on the cross plate 3 and disposed adjacent the I-beams 1 and 2. Mounted upon the cross plate 4 is a similar pair of inclined blocks 105—105. Disposed in sliding engagement with the pair of blocks 104 is a pair of inclined blocks 106, and likewise in sliding engagement with the blocks 105 is a pair of inclined blocks 107. Each of the blocks 104 has a horizontal upper flat portion 104^a, and the blocks 105 have similar portions 105^a. The blocks 106 and 107 are carried by the platform. The platform, as herein shown, consists of a skeleton structure formed of angle bars 108 and 109 placed 30 so that one section of each angle bar is horizontal, while the other section is vertical and lies adjacent the frame sections 1 and 2 of the truck. Rigidly fixed to the underside of the horizontal sections of the angle bars 45 108 and 109 are plates 110, 111 and 112. The plate 112 is in the form of an angle iron with one edge extending upwardly above the surface of the angle bars 108 and 109. These plates, together with the angle bars 108 and 50 109, form, as above noted, a skeleton platform which is adapted to carry the load.

Secured to the bars 108 and 109 are the 55 inclined blocks 106 and 107, and these inclined blocks are disposed so as to have their inclined faces in contact with the inclined faces of the blocks 104 and 105. The blocks 106 are each provided with a lower flat portion 106^a and an upper horizontal flat portion 106^b. Likewise the blocks 107 each have 60 a lower flat portion 107^a and an upper flat portion 107^b. The range of movement of the blocks is such that, when the platform is at the lower extreme of its movement, the portions 106^b and 107^b rest upon the flat faces 65 104^a and 105^a, and then again, when the

platform is at the extreme upper end of its movement, the flat sections 106^a and 107^a rest upon the flat sections 104^a and 105^a, respectively. These flat sections serve as a means for carrying the load when the platform is 70 at the extreme ends of its movement, and thus take the strain off from the operating mechanism which raises and lowers the platform. A bracket 113 is secured to the plate 75 111 and the rod 103 is pivoted to this bracket. 75

From the above description it will be noted that as the shaft 91 rotates, the crank piece 102 will be rotated, and this operating through the rod 103 will pull the platform in one direction or push the platform in the 80 opposite direction. A pull on the platform will cause the inclined blocks 104 and 105, thus raising the load, and then again, through a movement of the crank piece 102 and a push on the rod 103, the inclined blocks will slide down upon each other and gradually lower the load. The range of movement of the crank piece is such as to bring the flat portions 106^a and 107^a above 85 the flat portions 104^a and 105^a, respectively, so that the weight is carried by these flat portions rather than by the inclined faces of the blocks, and this takes the weight off of the crank piece 102. 90

As a means for automatically stopping the motor when the platform has reached the extremes of its movement, I have provided the crank piece 102 with diametrically opposed ears 114 and 115. The ear 114 carries 100 a pin 116, and the ear 115 carries a pin 117. The pins are an equal distance from the center of rotation of the crank. Pivoted upon the sides of the gear box 88 at a point 118 is a trip lever 119. Said trip lever is 105 pivoted nearer one end than the other so that the weighted end of the lever 119, when said lever is free, lies in the path of travel of the pins 116 and 117. Secured to the top of the gear box 88 are two brackets 120 110 and 121 in which is freely journaled the shaft 122. This shaft carries an arm 125. A spring 126 is secured at one end to said arm, and at the other end to the gear housing, and serves as a means for rotating the 115 shaft 122 in a counterclockwise direction. The lower end 128 of the arm 125 is adapted to make contact with the end 129 of the lever 119. Projecting upwardly from the shaft 122 is an arm 124 which is pivotally connected to a link 140, which in turn is pivoted to a hand lever or controlling lever 141 pivoted at 142 to the bracket plate 7. An upward movement of the end of the hand lever 141 will move the shaft 122 in 120 a clockwise direction and swing the arm 125 against the force of the spring 126. 125

Mounted on the gear casing or box 88 is a controller 130 for the motor. Said controller is of the usual construction for 130

giving one speed to the motor, and the controller is connected to and operated by a rod 137 which is connected by a link 138 to an arm 123 projecting upwardly from the shaft 122. The upward movement of the outer end of the hand lever 141 turning the shaft 122 in a clockwise direction pushes in on the rod 137 and closes the controller so as to permit the current from the battery to flow to the motor. Assuming that the gear 74 is in mesh with the gear 85, the motor will turn the gear 85, and through the reduction gearing turn the shaft 91 and raise or lower the platform, depending upon the position of the crank piece 102. Just as soon as the pins 116 and 117 move from the extreme upper vertical position, the weighted end of the lever 119 is released so that it drops, throwing the end 129 into the path of movement of the arm 125. If the operator releases the hand lever 141, the spring merely pulls the arm 125 against the end of the trip lever 119, and the parts will remain locked in this position until the crank piece 102 has moved through an arc of 180° or thereabouts, which brings the other pin into contact with the lever, causing the same to be raised and throwing the end 129 downward out of the path of the lever 125, and the spring 126 will then at once oscillate the shaft 122 and throw the controller out, thus cutting off the current from the motor.

Mounted on the shaft 86 is a brake drum 143 around which is a brake band 144. This brake band is connected at the points 145 and 146 to a lever 147. This lever is in turn connected by a link 149 to an arm 148 extending downwardly from the shaft 122. It will at once be noted that when the shaft 122 is turned in a counterclockwise direction, as viewed in Fig. 6, then the lever 147 will be swung about its central fulcrum so as to force the brake band into contact with the brake drum. This is accomplished by the well-known positioning and proportioning of the parts of the lever. As a result, the motor is not only disconnected from its source of power when the platform reaches the extreme of its movement, but a brake is applied to the train of mechanism between the motor and the lift platform for stopping said train of mechanism.

In the present construction, no great harm would be done by the continued movement of the shaft of the crank piece 102 after the lift platform has reached either of the extremes of its movement, for the reason that after the crank piece is moved so as to raise the platform a continued movement of the crank piece will lower the platform, but it is desirable to stop the lift platform when the flat portions of the inclined blocks are in engagement, and also when the load is clear up or when the platform is clear

down. It is understood that these industrial trucks are used in connection with tables or carriers having supporting legs of such height as to permit the truck to be driven by the operator underneath the table, and then, when the platform is raised, the table is lifted thereby, thus taking the load from the ground or floor. For this reason, it is extremely desirable that the lift platform shall be stopped in its movements up and down when either at its extreme lower position or at its extreme upper position. This is accomplished by the automatic means for cutting out the controller and applying the brake. It will also be noted that as soon as the mechanism is set into operation for lifting the load, the operating mechanism is out of control of the operator and is under the control of the latch lever 119 until the parts have moved through the desired distance, when the latch lever is released, the controller automatically cut out, and the brake applied.

In order that the motor may operate to raise the lift platform, the pinion 74 must be placed in mesh with the gear 85. This is accomplished by shifting the lever 82. When the lever 82 is in the position shown in Fig. 2 of the drawings, then the rod 81 is pulled so as to compress the spring 79^d, and this presses against the lug 79^a, forcing the fork 79 sidewise, said fork sliding on the pin 80, and through its connection with the sleeve 73 said fork will force the pinion 74 into mesh with the pinion 85. It is noted that this pressure brought to bear on the pinion 74 to cause it to mesh with the pinion 85 is a yielding pressure and just as soon as the teeth of the pinion gear are brought so that they can mesh, then they will slip into each other. When the lever is thrown in the opposite direction, then through the spring 79^c the fork is forced so as to cause the pinion 74 to mesh with the internal gear 67. The clutch gear 67 and gear 85 are so disposed that the pinion is either in mesh with one or the other or both of the gears at all times. There is no intermediate position when the gear is out of mesh with both pinions. This means that the motor is always connected with either the train of mechanism for propelling the truck or the train of mechanism for raising or lowering the platform.

The battery current for operating the motor for propelling the truck is controlled by an automatic switch 150. The wires leading to the switch are connected at 150^a and 150^b. The switch is controlled by a rod 151.

When this rod is in its raised position, the switch, which is the ordinary knife switch is closed and the wires 150^a and 150^b are connected. The rod 151 is connected to a brake lever 152 which in turn is connected to a brake strap 153 encircling a drum 154.

formed on the outer face of the internal gear 67. A spring 152^a connected at 155 to the lever 152 pulls down on the rod 151 and tends to disconnect the switch and also to apply the brake strap to the drum to place a brake upon the movement of the parts which are connected to the driving wheels for propelling the same. The rod 151 is connected to the lever 152 through a link 156.

10 Mounted at the forward end of the truck is a step-board 162. Said step-board is carried by arms 160 and 161, which are journaled upon a rod 157. Said arm 160 is provided with a shoulder 163. A pin 164 (see Fig. 13) is mounted in a casing 165 and spring-pressed against the shoulder 163 by the compression spring 166. Said spring is seated against the adjustable abutment 167 threaded into the casing 165. By adjusting this abutment, the pressure of the spring may be varied. The arm 161 has a similar shoulder against which a similar spring-pressed pin bears. These springs 166 are 20 of sufficient strength to cushion the weight of an operator standing on the step-board 162, and by adjusting the abutment 167 the springs may be made to suit the weight of the operator. Also journaled on the rod 157 is a foot lever 158, and this foot lever is connected by the rod 159 to the lever 152 which operates the rod 151 and the brake band 153. The step-board, when released from the weight of the operator, is raised 30 up against the foot lever 158. The operator standing on the step-board presses on the foot lever so as to raise the rod 151, close the switch, and also shift the lever 152 to release the brake. When the operator steps 35 off of the step-board or releases the foot-lever, then the upward movement of the foot lever and the upward movement of the step-board will cause the rod 151 to move downward, opening the switch, and shifting the 40 lever 152 to apply the brake.

45 As a means for controlling the motor for propelling the truck, I have provided a controller, indicated at 177 in the drawings. Said controller is of the usual construction and may be provided with three forward speeds and three reverse speeds accomplished by connecting the circuits of the motor in certain relations to each other. The controller is operated by a rod 176 which is 50 connected to an arm 175, and this arm is in turn connected to a link 174 connected to the lower end of a rod 173. The rod 173 is pivoted to a link 172 which in turn is 55 connected to the hand lever 171 pivoted to the bracket plate 7. By moving the hand lever 171 in one direction, the controller 177 is operated so as to give the first forward speed, or the second forward speed, or the 60 third forward speed. By moving the lever 65 in the opposite direction, then the reverse

motion of the motor is given and the truck driven in the opposite direction. It is not through necessary to go into the details of this controller as it may be of any suitable construction to bring about a proper driving 70 of the truck. The essential feature, however, consists in a controller which has a neutral position so that the controller may be thrown entirely out of operation and the motor stopped and a second or independent 75 controller used for actuating the motor for moving the lift platform up and down. Another essential feature of the controller consists in the forward and reverse movements of the truck brought about through the 80 movements of the motor, which are directly connected to the truck propelling wheels and remain in connection for all speeds and for the forward and backward travel of the truck.

85 In operation, the operator stands upon the step-board and he presses the foot lever 158, which will close the switch and release the brake on the driving mechanism for the truck. The lever 82 is then shifted to cause 90 the pinion or gear 74 to mesh with the internal clutch gear 67. This connects the motor with the driving wheels 28 and 35. The hand lever 171 is then either raised or lowered, depending upon which way it is 95 desired to propel the truck, and the truck may be moved forward at different speeds or backward. When the truck is under motion, it is impossible to shift the lift platform or load carrying means as the 100 motor is entirely disconnected from the elevating means, that is, the means for raising and lowering the platform. Assuming the platform is down and it is desired 105 to lift a load, the truck is driven so as to 110 carry the platform underneath the load, after which the truck is stopped. The hand lever 82 is then shifted to bring the pinion out of mesh with the internal gear and thus disconnect the motor entirely from the 115 driving wheels, and at the same time connect the motor with the reduction gearing which operates the crank piece 102 and thus raises and lowers the platform. The hand lever 141 is then operated so as to close the 120 controller 130 and connect the motor to the battery so that the train of mechanism will be set into operation and the crank piece 102 rotated. When the crank piece has traveled a proper distance to raise the platform to 125 its extreme upper position, then the trip lever releases the arm 125 which is automatically thrown by the spring 126 to cut out the controller 130 and apply the brake to the moving parts and thus stop the lift platform at its extreme upper position. Likewise, when the lift platform is at its 130 extreme lower position, the controller is automatically cut out.

From the above, it will be noted that I 130

have provided an industrial truck wherein a single motor may be utilized for either propelling the truck or raising and lowering the platform which supports the load, and 5 the operation of the truck and also the movement of the platform are electrically controlled, as distinguished from the use of shifting clutches. By this arrangement, the motor is always connected with either one 10 train of mechanism or the other, and all likelihood of the overspeeding of the motor is done away with. Furthermore, the control of the lifting mechanism is very much more efficient as the motor is connected 15 therewith when the stopping of the movements of the parts is brought about, and this aids greatly in the ease with which the parts may be stopped.

It is obvious that minor changes may be 20 made in the details of construction and the arrangement of the parts without departing from the spirit of the invention as set forth in the appended claims.

Having described my invention, I claim,

25 1. An industrial truck including in combination, a supporting frame, supporting and driving wheels therefor, elevating and carrying means mounted on the frame, a brake for said elevating means, a motor, 30 means for connecting said motor either to the driving wheels for propelling the truck or to the elevating means for lifting the load, a controller for the motor, whereby 35 said motor may be operated in either direction when connected to the driving wheels, a separate controller for the motor, whereby 40 said motor may be operated in either direction when connected to the elevating means, and automatic means for throwing out said last named controller and applying the brake when the elevating means reaches predetermined positions.

2. An industrial truck including in combination, a supporting frame, supporting and driving wheels therefore, elevating and carrying means mounted on the frame, a brake for said elevating means, a motor, a 45 shiftable device for connecting said motor either to the driving wheels for propelling the truck or to the elevating means for lifting the load, a controller for the motor, whereby 50 said motor may be operated in either direction when connected to the driving wheels, a separate controller for the 55 motor, whereby said motor may be operated when connected to the elevating means, and automatic means for throwing out said last named controller and applying the brake when the elevating means reaches the predetermined positions.

3. An industrial truck including in combination, a supporting frame, supporting and driving wheels therefor, elevating and carrying means mounted on the frame, a 60 brake for said elevating means, a motor,

means for connecting said motor either to the driving wheels for propelling the truck or to the elevating means for lifting the load, a controller for the motor, whereby 65 said motor may be operated in either direction when connected to the driving wheels, a separate controller for the motor, whereby 70 said motor may be operated when connected to the elevating means, an oscillating shaft connected to said last named controller, a lever connected to said shaft, a spring for moving said lever for throwing the controller to stop the motor, a latch for holding 75 said lever from movement by said spring, and means for releasing the latch when the 80 elevating means reaches predetermined positions.

4. An industrial truck including in combination, a supporting frame, supporting and driving wheels therefor, elevating and carrying means mounted on the frame, a 85 brake for said elevating means, a motor, means for connecting said motor either to the driving wheels for propelling the truck or to the elevating means for lifting the 90 load, a controller for the motor, whereby 95 said motor may be operated in either direction when connected to the driving wheels, a separate controller for the motor, whereby said motor may be operated when connected to the elevating means, an oscillating shaft connected to said last named controller, a lever connected to said shaft, a spring for moving said lever for throwing the controller to stop the motor, a latch for holding 100 said lever from movement by said spring, means for releasing the latch when the elevating means reaches predetermined positions, and a brake for said elevating means controlled by said shaft, whereby 105 said brake is applied when the controller is shifted to stop the motor.

5. An industrial truck including in combination, a supporting frame, supporting and driving wheels therefor, a load carrying platform mounted on the frame, raising and lowering means for said platform, a motor, means for connecting the motor to the driving wheels for propelling the truck, means for connecting the motor to the raising and lowering means for raising and lowering the platform, a controller for the motor whereby said motor may be operated in either direction when connected to the driving wheels, a second controller for the motor whereby said motor may be operated when connected to the raising and lowering means, and automatic means for throwing out said last-named controller when the platform reaches predetermined extreme positions.

6. An industrial truck including in combination, a supporting frame, supporting and driving wheels therefor, a load carrying platform mounted on the frame, rais-

ing and lowering means for said platform, a 5
brake for said raising and lowering means, a
motor, means for connecting the motor to
the driving wheels for propelling the truck,
means for connecting the motor to the raising
10 and lowering means for raising and
lowering the platform, a controller for the
motor whereby said motor may be operated
in either direction when connected to the
driving wheels, a second controller for the
15 motor whereby said motor may be operated
when connected to the raising and lowering
means, and automatic means for throwing
out said last-named controller and applying
the brake when the platform reaches pre-
determined extreme positions.

7. An industrial truck including in com-
bination, a supporting frame, supporting
and driving wheels therefor, elevating and
20 carrying means mounted on said frame, a
motor, a train of gears for operating the
elevating means, an independent train of
gears for operating the driving wheels, a
25 gear connected to said motor and shiftable,
whereby independent connection may be
made between the motor and said trains of
gears for independently operating either the
truck or the elevating means, said gear con-
30 nected to the motor being so disposed as
to be in partial engagement with both of
said trains of gears while shifting from
one train of gears to the other, whereby said
motor is at all times connected with one of
35 said trains of gears, and means for shifting
said gear connected with the motor includ-
ing a lever and interposed springs, a stop
for holding said lever in either of its ex-
treme positions and said springs operating
40 to cause a meshing of the gear connected
with the motor with the gears of the respec-
tive trains of gears for operating the elevat-
ing means and the driving wheels.

8. An industrial truck including in com-
bination, a supporting frame, supporting
45 and driving wheels therefor, a lift table
mounted on said frame, devices for raising
and lowering said table when said table is
moved endwise of the truck, a shaft, a crank
carried by said shaft, a link connecting said
50 crank to said table for moving said table
endwise, a motor, a train of gears connect-
ing said motor with said shaft, a controller
for said motor, an oscillating shaft con-
nected to said controller, a depending lever
55 carried by said oscillating shaft, a spring
for moving said shaft to operate the con-
troller to stop the motor, a latch for hold-
ing said lever against the action of the
spring and with the controller closed, op-
60 positely disposed members carried by the
shaft for operating the lift table and adapt-
ed alternately to engage the latch to re-
lease the lever so as to stop the motor when
said table is in extreme raised and lowered
65 positions.

9. An industrial truck including in com-
bination, a supporting frame, supporting and
driving wheels therefor, a lift table mounted
on said frame, devices for raising and lower-
ing said table when said table is moved 70
endwise of the truck, a shaft, a crank car-
ried by said shaft, a link connecting said
crank to said table for moving said table
endwise, a motor, a train of gears connect-
ing said motor with said shaft, a controller 75
for said motor, an oscillating shaft con-
nected to said controller, a depending lever
carried by said oscillating shaft, a spring
for moving said shaft to operate the con-
troller to stop the motor, a latch for holding 80
said lever against the action of the spring
and with the controller closed, oppositely
disposed members carried by the shaft for
operating the lift table and adapted alter-
nately to engage the latch to release the 85
lever so as to stop the motor when said
table is in extreme raised and lowered posi-
tions, a brake for said train of gears, and
means operated by said oscillating shaft
connected to the controller for applying 90
the brake when the motor is stopped.

10. An industrial truck including in com-
bination, a supporting frame, supporting
and driving wheels therefor, a lift table 95
mounted on said frame, devices for raising
and lowering said table when said table is
moved endwise of the truck, a shaft, a
crank carried by said shaft, a link connect-
ing said crank to said table for moving said
table endwise, a motor, a train of gears 100
connecting said motor with said shaft, a
controller for said motor, an oscillating
shaft connected to said controller, a depend-
ing lever carried by said oscillating shaft,
a spring for moving said shaft to operate 105
the controller to stop the motor, a latch for
holding said lever against the action of the
spring and with the controller closed, op-
positely disposed members carried by the
shaft for operating the lift table and 110
adapted alternately to engage the latch to
release the lever so as to stop the motor
when said table is in extreme raised and
lowered positions, a train of gears connected
115 with the driving wheels, and means for
disconnecting the motor from said train of
gears connected with the shaft for raising
and lowering the table and for connecting
said motor with the train of gears connected
120 to the driving wheels.

11. An industrial truck including in com-
bination, a supporting frame, supporting
and driving wheels therefor, elevating and
carrying means mounted on the frame, a
brake for the carrying means, a brake for
the driving wheels, a motor, a shiftable de-
vice for connecting the motor to the driving
wheels for propelling the truck or the ele-
vating means for lifting the load, a con-
troller for the motor, whereby the motor 125
130

may be operated in either direction, means for operating said controller and the brake for the driving wheels, whereby when the

to release the arm when the platform reaches predetermined extremes of movement.

- 5 the controller is positioned so as to disconnect the motor the brake is applied, a separate controller for the motor, whereby said motor may be operated when connected to the elevating means, and automatic means for throwing out said last named controller and 10 applying the brake to the elevating means when said elevating means reaches predetermined positions.

12. An industrial truck including in combination, a supporting frame having blocks 15 formed with inclined faces terminating at their upper ends in horizontal flat faces, a platform having inclined blocks associated with each block on the frame, said blocks on the platform having inclined faces terminating both at their upper and lower ends in flat horizontal faces, said blocks being disposed so that the flat faces at the lower ends of the inclines on the platform will rest on the flat faces at the upper ends of the 20 inclines on the frame when the platform is raised, and the flat faces at the upper ends of the inclines on the platform will rest on the flat faces of the blocks on the frame when the platform is in its lowered position, 25 means for raising and lowering the platform, a motor connected with said means, a controller for said motor, and automatic means for cutting out the controller when the flat faces are brought into engagement 30 with each other.

13. An industrial truck including in combination, a supporting frame, a platform, means for raising and lowering the platform when the platform is moved endwise 40 relative to the frame, means for moving the platform endwise including a rotating shaft, a crank piece carried thereby, a motor, reduction gearing between the motor and the shaft carrying the crank piece, a controller 45 for said motor, an oscillating shaft connected to the controller, a hand lever connected to said oscillating shaft, a depending arm carried by the oscillating shaft, a spring connected thereto for moving the shaft to open 50 the controller, a latch for controlling the movements of said arm, and means movable with the crank piece for lifting the latch

14. An industrial truck including in combination, a supporting frame, a platform, means for raising and lowering the platform when the platform is moved endwise relative to the frame, means for moving the 55 platform endwise including a rotating shaft, a crank piece carried thereby, a motor, reduction gearing between the motor and the shaft carrying the crank piece, a controller for said motor, an oscillating shaft connected to the controller, a hand lever connected to said oscillating shaft, a depending arm carried by the oscillating shaft, a spring connected thereto for moving the shaft to open the controller, a latch for controlling the 60 movements of said arm, arms extending laterally from the crank piece and carrying diametrically opposed pins adapted to engage the latch for releasing the same when the platform reaches predetermined extremes of movement.

15. An industrial truck including in combination, a supporting frame, a platform, means for raising and lowering the platform when the platform is moved endwise 65 relative to the frame, means for moving the platform endwise including a rotating shaft, a crank piece carried thereby, a motor, reduction gearing between the motor and the shaft carrying the crank piece, a controller 70 for said motor, an oscillating shaft connected to the controller, a hand lever connected to said oscillating shaft, a depending arm carried by the oscillating shaft, a spring connected thereto for moving the shaft to open the controller, a latch for controlling the 75 movements of said arm, arms extending laterally from the crank piece and carrying diametrically opposed pins adapted to engage the latch for releasing the same when the platform reaches predetermined extremes of movement.

Buffalo, N. Y., July 11, 1917.

WILLIAM H. WRIGHT.
